MACHINE FOR FORMING FLANGED END
WALLS FOR CONTAINERSSwan Smith, White Bear, Minn., assignor to
David C. Shepard, St. Paul, Minn.

Application March 6, 1937, Serial No. 129,393

27 Claims. (Cl. 93—36)

My invention relates to machines for forming laminated flanged end walls for containers and has for an object to provide a machine by means of which such end walls may be automatically constructed.

Another object of the invention resides in providing a machine of such character in which the paper is unreeled from a single roll and successively operated upon to produce the final ultimate structure.

10 An object of the invention resides in providing a machine of the character described by means of which a number of sheets are cut from a roll of paper and glued and assembled together to form a composite blank.

A still further object of the invention resides in providing a machine in which certain of the sheets and preferably alternate sheets are rotated through certain angles so that the grain in the sheet runs in several directions in the blank.

20 Another object of the invention resides in providing a gluing device by means of which certain of the sheets fed to the same are coated on one surface with glue and in further providing a mechanism whereby certain others of the sheets pass the gluing device without being coated so that the uppermost and lowermost sheets of the stack of sheets have their upper and lower surfaces free from glue.

30 An object of the invention resides in providing an assembling device in which the glued sheets are first held by temporary supports and adjusted in proper position and then deposited upon the other sheets of the stack.

35 A feature of the invention resides in providing a trimmer by means of which the blank formed from the assembled sheets is cut circular in form and in which the blank is rotated while engaged by a cutter having a fixed situs relative to the machine.

40 Another object of the invention resides in providing a press constructed with a die having a cylindrical bore and a plunger movable within said bore to force the circular blank into the same and form a flange thereon.

45 A feature of the invention resides in providing a machine in which the strip of paper, the sheets cut therefrom and the blanks formed from the sheets are automatically and positively fed to and from the various mechanisms of the invention which operate thereon.

50 Other objects of the invention reside in the specific construction of the various mechanisms operating upon the sheets and in the relation of these mechanisms to one another.

In the drawings:

Fig. 1 is a plan view of a machine for making flanged end walls for paper containers showing an embodiment of my invention.

Fig. 2 is an elevational view of the machine shown in Fig. 1 viewed from the near side thereof.

Fig. 3 is an elevational view of the machine shown in Fig. 1 and viewed from the far side thereof.

Fig. 4 is a fragmentary cross sectional view taken on line 4—4 of Fig. 1.

Fig. 5 is a longitudinal sectional detail view of a portion of the paper feeding mechanism taken on line 5—5 of Fig. 1.

Fig. 6 is a similar view of another portion of the paper feeding mechanism taken on line 6—6 of Fig. 1.

Fig. 7 is a fragmentary elevational sectional view taken on line 7—7 of Fig. 1.

Fig. 8 is a view similar to Fig. 7 showing the parts in altered position.

Fig. 9 is a vertical sectional detail view of a portion of the paper turning device taken on line 9—9 of Fig. 1.

Fig. 10 is a view similar to Fig. 9 of another portion of the turning device taken on line 10—10 of Fig. 1.

Fig. 11 is a vertical sectional view of the assembling device and ironing rolls of the invention taken on line 11—11 of Fig. 1.

Fig. 12 is a cross sectional view of the machine taken on line 12—12 of Fig. 1.

Fig. 13 is a cross sectional view of the ironing rolls and associated structure taken on line 13—13 of Fig. 1.

Fig. 14 is a cross sectional view of the machine taken on line 14—14 of Fig. 1.

Fig. 15 is a longitudinal sectional view of a portion of the conveyor mechanism for feeding the assembled blanks to the press, and taken on line 15—15 of Fig. 1.

Fig. 16 is a longitudinal vertical sectional view taken through the press.

Fig. 17 is an elevational view of a portion of the press operating mechanism viewed from the far side of the machine as disclosed in Fig. 1.

Fig. 18 is a vertical sectional view taken on line 18—18 of Fig. 12.

Fig. 19 is a cross sectional view taken on line 19—19 of Fig. 12.

In the construction of laminated circular paper containers such as butter tubs and the like, it becomes desirable to form flanged end walls for the containers. A flanged end wall of lesser

dimensions than the side wall of the container is inserted within the lower end of the same and forms a bottom for the container. A flanged end wall of larger dimensions than the side wall of the container fits over the top of the same and forms a removable closure. The present invention provides a machine by means of which both end walls of the containers can be automatically constructed.

10 My invention comprises a reel A on which a roll of paper 20 is mounted and from which a strip 21 unrolled from the roll is carried through the machine. The strip 21 passes through a paper tensioning device B by means of which the paper is properly directed to a paper feed mechanism C. The paper feed mechanism C operates intermittently to unroll sections of the strip which are cut off into individual sheets by a cut off device D for assembly into the composite container end. Prior to severance of the strip the same is notched by means of a notching device E so that the individual sheets become octagonal in form, whereby the same may be more conveniently manipulated as the sheets are operated 15 upon by the machine. The individual sheets are deposited upon a turning device F which rotates every alternate sheet and discharges the same upon a conveyor G. The conveyor G delivers the sheets to a gluing device H which applies glue 20 to a certain number of sheets in succession. By means of a skip gluing mechanism I each seventh sheet in the particular form of the invention shown is deprived of glue so that the exposed surface of the sheets of the stack forming the end wall blank are without glue. From the gluing device the sheets are delivered to an assembling device J where the same are placed one upon another with the lowermost and uppermost sheets arranged with the unglued surfaces lowermost and uppermost. A feed mechanism K takes the sheets from the assembling device and delivers them to ironing mechanism L where the sheets are firmly pressed together to form a compact structure. A conveyor M delivers the sheets from the ironing mechanism to a trimmer N by means of which the composite structure is cut circular 25 in form to form a blank suitable for insertion into the press P. The conveying mechanism O moves the trimmed blank from the trimmer to the press. 30 After the blank has passed through the press the same is discharged from the machine through a discharge device Q. These various parts and the framework for supporting the same together with the driving mechanism therefor will now be described in detail.

35 The framework of the invention consists of two longitudinal frame members 22 and 23 which rest upon the floor or other structure on which the machine is to be supported. These frame members are tied together by means of transverse frame members 24, 25 and 26. At the far end of the machine are provided two uprights 27 and 28 and intermediate the ends of the frame members 22 and 23 are provided similar uprights 31 and 32. The two uprights 31 and 27 are connected together by means of a longitudinal frame member 33, while the uprights 28 and 32 are similarly connected together by a longitudinal frame member 34. The two uprights 27 and 28 are secured together by means of a transverse frame member 35 which is constructed with flanges 36 bolted to the upper ends of the said uprights. In a similar manner an angle frame member 37 connects the two uprights 31 and 32 together. In between the horizontal frame members 22 and

33 is provided an upright 38 which is disposed intermediate the ends of the frame member 33. A corresponding upright 39 is disposed between the longitudinal frame members 31 and 32.

For the purpose of driving the various mechanisms and devices of the invention, an electric motor 42 is employed which is best shown in Fig. 3. This motor is mounted on a plate 43 secured to the longitudinal frame member 22. The motor 42 has an armature shaft 44 which carries a 10 pulley 45. A belt 46 passes over this pulley and another pulley 48. The pulley 48 is secured to a sleeve 49 which in turn has attached to it a spur pinion 51. The sleeve 49 is rotatable on a stub shaft 52 which is rigidly mounted in a 15 bracket 53 secured to upright 31 of the framework of the invention, as best shown in Fig. 8. The stub shaft 52 is held attached to said bracket by means of a nut 54 and the other end of said shaft enlarged to hold the sleeve 49 rotatably 20 mounted thereon. The pinion 51 meshes with a spur gear 55 constituting one of the gears of a gear cluster 56. This gear cluster includes the gear 55 and another pinion 57. The gear cluster 56 is rotatable on another stub shaft 58 which 25 is secured to the bracket 53 by means of a nut 59. The pinion 57 meshes with a gear 61 which is one of the gears of a gear cluster 62. The gear cluster 62 includes a pinion 63 and is mounted for rotation on a stub shaft 64 which is 30 directly attached to the upright 31 by means of a nut 65. The pinion 63 meshes with a large spur gear 66 which is rigidly attached to the main drive shaft 67. Main drive shaft 67 is journaled in bearings formed in the uprights 31 and 32 35 which have not been illustrated in the drawings. The shaft 67 extends completely across the machine and is provided at its other end as shown in Fig. 2 with a bevel gear 68. This bevel gear meshes with a bevel gear 69 fast on a longitudinally extending countershaft 71 arranged in close proximity to the longitudinal frame member 34. The shaft 71 is journaled in a bearing 72 mounted on upright 32 and in another bearing 73. Attached to the rearward portion of the two uprights 27 and 28 are two rearwardly extending brackets 74 and 75. These brackets are connected together at their outermost ends by means of a U-shaped frame member 76. The bearing 73 supporting the end of shaft 71 is attached to the bracket 75. In addition to the two bearings 72 and 73 another bearing 77 is provided for shaft 71 which is disposed intermediate the ends of the same. This bearing is attached to the longitudinally extending frame member 34. The shaft 71 has secured to the rearward end thereof a bevel gear 78. This gear meshes with another bevel gear 79. This bevel gear is one of the gears of a gear cluster 81 which is rotatably mounted on a stub shaft 82. This is 40 best shown in Fig. 15. The other gear of this gear cluster is a spur pinion 83 which meshes with a spur gear 84 also shown in Fig. 2. Spur gear 84 is fast on a shaft 85 which extends across the two brackets 74 and 75 and is journaled in bearings 86 and 87 secured to said brackets. All of the parts of the invention are driven from these various shafts as will be presently more fully described.

The reel A on which the roll of paper 20 is 70 supported consists of two standards 88 and 89 which are secured to the longitudinal frame members 22 and 23. These standards, as best shown in Fig. 1, are provided with sockets 91 into which may be set a shaft 92. Shaft 92 75

serves as an arbor for the roll and is provided with collars 93 and 94 which hold the roll properly in position thereon. The ends of the shaft 92 extend beyond the collars 93 sufficiently so that the same may be grasped by a crane, whereby the said arbor may be dropped into or raised out of the sockets 91.

From the roll 20 the unrolled strip 21 passes through the paper tensioning device B. The tensioning device B is supported on two standards 95 and 96 which are secured to the longitudinal frame members 22 and 23 and are braced from the uprights 31 and 32 by means of braces 90. As best shown in Fig. 4 two brackets 97 and 98 are secured to said standards in a manner to be presently described in detail. These brackets are held in proper spaced relation by means of a tie rod 99. Two rolls 101 and 102 are journaled in bearings 103 formed in the brackets 97 and 98. These rolls are arranged so that the roll 102 is forward of the roll 101 and so that the upper portion of said roll is above the lower portion of the roll 101. The strip 21 passes in between these rolls and is slightly tensioned thereby so that the paper is kept taut while traveling through the machine.

The paper strip 21 is fed from the tensioning device B to the cut off device D by means of the paper feed mechanism C. This feed mechanism is best shown in Figs. 1, 2, 3 and 6. Extending across the two longitudinal frame members 22 and 23 is a shaft 104 which is journaled in bearings 105 and 106 secured to the same. The shaft 104 has attached to it two vertically extending arms 107 and 108 which have secured to their upper ends a cross bar 109. Bar 109 is fast to the arms 107 and 108 and carries a gripper finger 111 which is rigidly secured thereto. Below the bar 109 is a shaft 112 which is journaled for rotation in bearings 113 formed in the arms 107 and 108. This shaft carries a complementary gripper finger 114 and upon rotation of the particular shaft, finger 114 is brought into engagement with finger 111 to grip the strip 21 of paper passing between the same.

The paper feed mechanism C is operated in the following manner: Attached to the shaft 112 in close proximity to arm 107 is a depending arm 115 which has pivotally connected to it a link 116. This link is in turn pivotally connected to a crank pin 117 mounted on a bracket 110 attached to the gear 66 previously referred to. The arm 115 has a lug 118 secured to the same which is adapted to engage the arm 107 to limit the rotation of shaft 112 in one direction. Engagement of the fingers 114 and 111 limits the movement of the shaft 112 in the opposite direction. It will thus be comprehended that as the shaft 67 rotates, crank pin 117 is carried around with it and the two arms 107 and 108 oscillate back and forth. As the arms 107 and 108 travel away from the tensioning device B the actuating force is transmitted through arm 115 and the finger 114 forced against finger 111. This grips the paper and advances the paper through the machine. When the arms 107 and 108 are moved in the opposite direction the force being again transmitted through arm 115, said arm is first moved so that the finger 114 is disengaged from the finger 111. As soon as lug 118 engages arm 107, the arms 107 and 108 travel toward the tensioning device B and during such movement the fingers 111 and 114 being spaced travel freely along the paper without feeding the same.

For the purpose of stabilizing the action of the paper feeding mechanism, a cross head 119 is em-

ployed which is attached to shaft 104. This cross head has pivoted to it two plungers 121 and 122. These plungers are slidably mounted in a guide-way 123, Fig. 7, which is secured to the longitudinal frame member 22. By means of this construction, the plungers 121 and 122 may reciprocate in a vertical direction as the shaft 104 oscillates. Encircling the two plungers 121 and 122 are compression coil springs 124 which are seated against the guide 123 and against collars 125 fast on said plungers. These springs stabilize the movement of the feed mechanism, preventing a jerky operation of the same.

In order to move advantageously handle the sheets of paper which are built into the blank for constructing the container end walls it is desirable that the said sheets be octagonal in form rather than square. To so form the sheets, the same are notched before being cut into sections, by means of the notching device E. This device is best shown in Figs. 1, 4 and 5. Attached to the two standards 95 and 96 are two brackets 136 and 137 and bolted thereto are two notched die blocks 126 and 127. Cooperating with said die blocks are two angle cutters 128 and 129 which are attached to arms 131 and 132. These arms are mounted on shafts 133 and 134 which are in turn journaled in forked bearings 136 and 137 secured to the die blocks 126 and 127. When the arms 131 and 132 are swung downwardly the cutters 128 and 129 cooperate with the die blocks 126 and 127 to cut notches in the strip 21 passing between the said cutters and die blocks.

The notching device D is operated in the following manner: Attached to the main drive shaft 67 is a spur gear 138, Fig. 2. This spur gear meshes with another spur gear 139. Gear 139 is mounted for rotation on a stub shaft 141 which is secured to a bracket 142 shown in Fig. 1 which is attached to upright 32. The gear 139 has secured to it a crank pin 143 which has pivoted to it one end of a connecting rod 144. Rod 144 has secured to it a collar 145 best shown in Fig. 1 which is adapted to engage one of the arms of a bell crank 146. The bell crank 146, as shown in Fig. 4, is pivoted to a bracket 147 which in is secured to the upright 96. The other arm of this bell crank is pivotally and slidably connected to the end of an arm 148 which is secured to the shaft 133 to which arm 131 is attached. It will be comprehended that as the connecting rod 144 is moved toward the left, as shown in Figs. 1 and 2, that the collar 145 engages bell crank 146 and swings the same in a manner to cause the cutter 128 to move downwardly and to engage the die block 126 and cut the sheet passing between said cutter and die block. For simultaneously operating cutter 129 a gear segment 149 is attached to the shaft 134 to which arm 132 is attached. A lever 151 is pivoted to the standard 95 by means of a bolt 152 and is constructed with a gear segment 153 which meshes with the gear segment 149. As this lever is operated the shaft 134 is turned in the opposite direction. A link 154 connects the arm 148 with lever 151. A tension coil spring 155 is connected to the link 154 and to the standard 95. This spring operates to raise the arms 131 and 132 and to move the cutters 128 and 129 out of engagement with the corresponding die blocks. It will thus become apparent that as the gear 139 rotates both the cutters 128 and 129 are simultaneously operated to notch the strip passing between said cutters and die blocks. Below the notching device D is disposed a chute 156 which collects the punchings from the notching 75

device and discharges the same into a suitable receptacle placed beneath the machine.

In order to prevent the notched sheet from jumping up from the die blocks 126 and 127 when the cutters 128 and 129 are raised, two guide fingers 157 and 158 are employed. These fingers are attached to a rod 159 which is rigidly secured to the uprights 95 and 96.

The notched strip 21 on leaving the notching device E is fed by means of the paper feeding mechanism C to the cut off device D. This device is best shown in Figs. 7 and 8, and includes a shaft 161 which is journaled in bearings 162 and 163 formed on the upper ends of the uprights 31 and 32. This shaft has secured to it a number of arms 164 which have attached to them a rotary cutter blade 165. This blade cooperates with a bed knife 166 which is attached to the transverse frame member 31. The shaft 161 rotates in a clockwise direction as viewed in Fig. 7, and engages the bed knife 166 to cut off the sections of the strip to form the sheets from which the end wall blank is constructed. The cutter D is so arranged that the line of severance 25 of the sheets from the strip occurs at the vertex of the notches formed by the notching device E so that the sheets severed become octagonal in form.

The shaft 161 is driven in the following manner: Attached to the end of this shaft is a spur gear 167, Fig. 2, which meshes with the spur gear 138 fast on the main drive shaft 67.

For the purpose of holding the paper from movement during the operation of the cut off device, a gripping mechanism is provided which is best shown in Figs. 3 and 7. This device comprises a movable gripper bar 168 which is attached to two arms 171 secured to a transverse shaft 172. This bar has a pad 169 attached to it which is adapted to engage the upper surface of the transverse frame member 31. Shaft 172 is journaled in bearings 173 secured to the uprights 31 and 32. This shaft as shown in Fig. 3 has attached to it an arm 174 which carries at its outer end a roller 175. Roller 175 engages a cam 176 fast on shaft 161. As the raised portion of the cam engages roller 175, the gripper bar 168 is moved away from the gripper bar 169 and the paper may travel freely between the two bars 168 and 169. By means of a tension coil spring 177 acting between one of the arms 171 and the transverse frame member 31, the gripper bars are brought together when the roller 175 engages the low portion of the cam 176.

The sections of the strip upon being severed by the cut off device D are deposited upon conveyor G, best shown in Figs. 7 and 8. This conveyor consists of two belts 178 and 179 which pass over pulleys 181 and 182 mounted on two shafts 183 and 184. Pivoted to the main drive shaft 67 are two arms 185 and 186. These arms are held in spaced relation by means of two rods 187 and 188 which have nuts 189 screwed upon the outer ends of the same. The two shafts 183 and 184 are journaled in bearings 191 and 192 formed in said arms and are held in proper position with respect thereto by means of the pulleys 181 and 182. The belts 178 and 179 also pass over idler pulleys 193 which are mounted in arms 70 194 attached to the rod 188. These arms are clamped between the ends of the rods 188 and arms 185 and 186 and are held in position by nuts 189 holding rod 188 attached to said arms 185 and 186. By means of this construction the 75 tension in the two belts 178 and 179 may be

regulated. The two arms 185 and 186 have counterweights 195 secured to the outer ends thereof so that the conveyor G is balanced. By means of this construction the conveyor may be moved from its position shown in Fig. 7 to that shown in Fig. 8, for the purpose of feeding the sheets to the gluing device and for the purpose of permitting the turning device to rotate the sheets.

The conveyor G is driven in the following manner: Attached to the main drive shaft 67 is a sprocket 196. A chain 197 passes over this sprocket and over two sprockets mounted on the shafts 183 and 184, not shown in the drawings. This chain drives both the shafts 183 and 184 and 15 in this manner procures rotation of the pulleys 181 and 182 in a direction to cause the upper runs of the belts 178 and 179 to travel toward the gluing device H.

The conveyor G is raised and lowered in the 20 following manner: Attached to the main drive shaft 67, as shown in Fig. 10, is a spur pinion 198. This spur pinion meshes with a spur gear 199 which is mounted for rotation on a stud 201 secured to the upright 32. The spur gear 199 has 25 attached to it a cam 202. An arm 203 pivoted at 204 to the upright 32 carries a roller 205 which engages the cam 202. Arm 203 has pivoted to it a link 206 which is also shown in Fig. 8. This link is in turn pivoted to the arm 186 of conveyor 30 G, whereby the said conveyor is raised and lowered as the roller 205 follows the cam 202.

The turning device F is best shown in Figs. 1, 3, 7, 8 and 10. Attached to the upright 32 is a bracket 207 which extends transversely of the machine and which is provided at its inner end with a bearing 208. Rotatably mounted in this bearing is a vertical shaft 209 which is situated centrally of the sheet severed by the cut off device E. This shaft has attached to the upper 40 end of the same a turntable 211 which is provided with a boss 212 secured to said shaft. The lower end of this boss has attached to it an outwardly extending arm 213. A sleeve 214 disposed between the boss 212 and the bearing 208 holds 45 the turntable 211 at the proper elevation. The upper portion of the turntable 211 is cupped as indicated at 215 for a purpose to be subsequently more fully described. The turntable 211 is oscillated through an angle of ninety degrees by 50 means of the arm 213. Pivoted connected to this arm is a link 216 which in turn is pivoted to an arm 217 attached to a shaft 218. Shaft 218 has mounted on it a sleeve 220. Shaft 218 is journaled in a bearing 210 secured to the longitudinal frame member 23 and in the sleeve 220 which in turn is journaled in another bearing 219 secured to the longitudinal frame member 22. 55

The shaft 218 has attached to it an upstanding arm 221. This arm has attached to it a cam 222. 60 This cam is adapted to be engaged by a roller 341 which is rotatably mounted on an arm 342 secured to shaft 71. As the roller 341 engages cam 222 shaft 218 is rocked and the arm 217 is likewise rocked and the turntable 211 rotated. 65

A drive between the turntable 211 and the sheet passing over the same is procured through a revoluble presser foot 231. This presser foot is rotatably mounted in a reciprocating rod 232 which is guided for vertical movement in a guide 70 233. Guide 233 is attached to an arm 234 which is constructed with a base 235 bolted to the longitudinal frame member 33. The rod 232 is pivoted to a lever 236 which is pivoted to a bearing 237 mounted on the horizontal frame member 33 75

as shown in Fig. 3. As seen in Fig. 3 lever 236 has pivoted to it a link 238 which in turn is pivoted to another lever 239. This second lever is pivoted at 241 to a hanger 242 which is attached to the horizontal frame member 33. The lever 239 carries a roller 243 which is adapted to engage a cam 244 best shown in Fig. 3. This cam is attached to a gear 245 which is mounted for rotation on a stub shaft 246 attached to the longitudinal frame member 33. Lever 239 has a counterweight 247 secured to the same, whereby said roller 243 is maintained in engagement with the cam. It will be noted that gear 245 meshes with another gear 248 which is attached to the main drive shaft 67. Gear 245 is twice the size of gear 248 so that the presser foot 231 is operated as every alternate sheet passes through the machine. It will be noted that the turntable 211 is turned each time a sheet is cut off by the cut off device E. However, since the presser foot 231 is only brought into engagement with the turntable 211 for each alternate sheet, every alternate sheet is rotated through an angle of ninety degrees and the other sheets are caused to pass through the machine without being turned.

When the sheets are taken from the innermost portion of the roll the sheets curve in such a manner that the same cannot be conveniently rotated by the turning device. By constructing the turntable 211 cupped as indicated at 215, the presser foot 231 is forced into the concavity which raises the corners of the sheets and permits the turntable to function in an efficient manner.

To arrest the movement of the sheets when delivered to the turning device A a number of fingers 294 are employed which are secured to a horizontally extending rod 295 disposed the proper distance from the turntable 211. This rod is fast on a swinging lever 296 which is pivoted at 297 to the horizontal frame member 34 as best seen in Figs. 2, 8, 9 and 10. This lever carries a roller 298 which engages a cam 299, Fig. 9, which is attached to the gear 199 which rotates on the stub shaft 201. Since the cam 299 is operated by gear 199 it also operates cam 202 raising and lowering the conveyor G. It becomes evident that the cam 299 must have two depressions 301 and 302 so that the sheets are arrested prior to entering the gluing device, both when the sheets travel through in the regular manner and when the sheets are rotated. The fingers 294 in addition to arresting the sheets cause the sheets to straighten out so that the same are squarely fed into the gluing device.

The sheets delivered upon the conveyor G are centered with respect to the turning device F by means of two adjusting plates 303 and 304 best shown in Fig. 19. These plates are attached to vertically extending arms 305 and 306 which are pivoted to bearings 307 and 308 secured to the longitudinal frame members 23 and 22. The arm 305 has secured to it a horizontally extending arm 309 while the arm 306 has secured to it a horizontally extending arm 311. The arm 309 is bifurcated as indicated at 314 and is constructed with a slot 313 extending through the end of the same. The extreme end of the arm 311 extends into the bifurcated portion 314 of arm 309 and is provided with a pin 312 secured thereto, which fits in the slot 313. By means of this construction the two adjusting plates 303 and 304 may travel simultaneously inwardly or outwardly.

For operating the adjusting plates 303 and 304

an arm 315 is employed which is pivoted in a bearing 316 secured to the frame member 23. A link 317 pivoted to this arm and to the arm 305 causes simultaneous movement of the two plates 303 and 304 upon swinging movement of the arm 315 in a vertical plane. Arm 315 has secured to the upper portion of the same a cam 318 which is adapted to be engaged by a cam roller 319 rotatably mounted upon the end of a short arm 321. This arm is rigidly secured to the shaft 11 previously referred to. The arm 321 is so positioned that the adjusting plates 303 and 304 move simultaneously with the fingers 294 to properly position the sheet with reference to the turntable 211 and also hold the sheet until the presser foot 231 is lowered into engagement with the sheet. Immediately thereafter the adjusting plates 303 and 304 are disengaged from the sheet and likewise the fingers 294. For the purpose of disengaging the adjusting plates 303 and 304 from the positioned sheets, a tension coil spring 322 is employed which is secured at one end to the arm 306 and at its other end to a support 323 secured to frame member 22. This spring normally holds the two plates away from the sheets and urges the cam 318 against the roller 319.

The gluing device H is best shown in Figs. 1, 7 and 8. This device includes two bearing blocks 251 and 252 which are attached to the longitudinal frame members 33 and 34. Between these bearing blocks is mounted a glue pan 253 which is supported by said blocks in any suitable manner. Journalized in suitable bearings formed in the bearing blocks 251 and 252 are two main glue rollers 254 and 255. A distributor roll 256 is also journaled in the said bearing blocks 251 and 252 and is adapted to press against the roll 255. This roll is adjustably urged against the roll 255 by means of adjusting screws 257 which operate in the customary manner to move the roll 256 toward the roll 255. The roll 255 is adapted to dip into the glue within the glue pan 253 and carries a film of glue over to the roll 254 which transfers it to the sheet passing beneath the same. The bearing blocks 251 and 252 also support a guide roll 258 which assists in moving the sheet to be coated to the main glue rolls 254 and 255.

For bringing the sheet to be coated in contact with the glue roll 254 two presser rolls 261 and 262 are employed. These rolls are journaled in two arms 260 and 263, Fig. 12, which are attached to a shaft 264. Shaft 264 is mounted for oscillation in bearings 259 formed in the longitudinal frame members 33 and 34. When the two rolls 261 and 262 are lowermost as shown in Fig. 8, the sheets passing over the same do not engage the roll 254 and the same are not coated with glue. When the rolls are raised as shown in Fig. 7, the sheet is brought in contact with the roll 254 and gluing of the sheet occurs. The feeding of the sheets to the glue roll 254 is procured by the conveyor G. This conveyor when elevated as shown in Fig. 7 brings the upper run of the belts 178 and 179 into contact with the roll 258 which procures a positive feed of the paper beneath the glue pan 253 and the roll 254. A flexible finger 265 engages the presser roll 262 and keeps the sheet more firmly in contact therewith. This assists in feeding the sheet and also prevents the sheet from rolling around the roll 254. When the rolls 261 and 262 are depressed as shown in Fig. 8 this finger 265 holds the sheet away from the roll 254.

To positively guide the sheets up to the roll 262 a number of arms 266 are employed which

are pivoted to the trunnions of the rolls 262 and which rest on the rod 187. These arms form runways along which the paper travels until the same is brought into engagement with the roll 5 262.

The various glue rolls are driven in a manner best shown in Figs. 2 and 18. Meshed with the gear 167 which is mounted on the shaft 161 is a spur gear 267 which is journaled on a stub shaft 10 268 secured to the longitudinal frame member 34. This gear meshes with another idler gear 269 which is similarly mounted on a stub shaft 271 also secured to the longitudinal frame member 34. The gear 269 meshes with a gear 272 15 which forms the larger gear of a gear cluster 273. This gear cluster is mounted for rotation on a stub shaft 274 secured to the longitudinal frame member 34. The smaller gear of this gear cluster which is not shown meshes with a gear 270, 20 being one of the gears of another gear cluster 275. This gear cluster is mounted on a stub shaft 276 which is also secured to the longitudinal frame member 34. Gear 275 meshes with a gear 277 secured to the trunnion of roll 254. 25 This roll trunnion has attached to it still another gear 278 which meshes with a gear 279 fast on the trunnion of roll 255. In this manner both rolls 254 and 255 are positively driven. The gear 278 also meshes with a pinion 281 fast on 30 the trunnion of roll 256 so that the said roll is correspondingly rotated. The two rolls 261 and 262 as shown in Fig. 18 are provided with sprockets 282 and 283. These sprockets engage a chain 284 which passes over a sprocket 285 on one of 35 the trunnions of roll 254 and which also passes over an idler sprocket 286 supported on a lever 287. This lever is pivoted to a bracket 288 attached to the longitudinal frame member 33 and carries a weight 289 by means of which the chain 40 284 is kept suitably tensioned. In this manner both the rolls 261 and 262 are positively driven. The roll 258 also has attached to one of its trunnions a sprocket, not shown. A chain 292, Fig. 3, passes over this sprocket and another sprocket 45 secured to a trunnion of the roll 254.

In order that the top sheet be free from glue so that both the top and bottom section are without glue upon their exposed surfaces, skip gluing mechanism I is utilized. This skip gluing mechanism embodies the two rolls 261 and 262 50 and the supports therefor and has for its purpose to move said rolls downwardly and away from the roll 254. The two arms 260 and 263 are mounted on the shaft 264 as previously explained and when the said arms are rocked the rolls 261 and 262 are lowered. For this purpose a depending arm 324, shown in Figs. 7 and 8, is employed which is attached to the arm 260. This arm has pivoted to it a link 325 which in turn is 55 pivoted to the upper end of another arm 326. Arm 326 is fast on the sleeve 220 which is journaled for oscillation in the bearings 219 mounted on frame member 22. As this shaft oscillates the rolls 261 and 262 are alternately raised and lowered to bring the sheet in contact with the roll 254 or to drop the sheet below the same.

The sleeve 220 is oscillated in the following manner: Attached to the sleeve is an upstanding arm 343 (Fig. 12) which has pivoted to the upper 70 end thereof a longitudinally extending link 344 shown in Figs. 3 and 17. This link extends rearwardly of the machine and is pivoted to a lever 346. Lever 346 is pivoted on a stud 228 which is secured to the bracket 74. This lever has rotatably mounted at its other end a roller 347

which is adapted to engage a cam 348. This cam is driven as follows: Attached to the transverse shaft 85 is a spur gear 223. This spur gear meshes with another spur gear 224 fast on a stub shaft 225 secured to the bracket 74. The 5 gear 224 has secured to it the cam 348. As the shaft 85 rotates, link 344 is reciprocated by cam 348 and the sleeve 220 oscillated to procure movement of the lever 324. This moves the rolls 261 and 262 from the positions shown in Fig. 8 10 to the position shown in Fig. 7 and vice versa.

In order to prevent the glued sheet from following around the roll 254 an idler roll 327 is employed which is rotatably mounted in bearings secured to a cross bar 328. This cross bar is 15 supported on two hooked brackets 329 which are secured to the bearing blocks 251 and 252. These brackets also provide bearings for a transverse shaft 331 which supports two depending hooked arms 332. Arms 332 rotatably support two small 20 rolls 333 which straddle the roll 327. The rolls 333 are disposed below the lowermost portion of the roll 254 and can be moved from the position shown in Fig. 8 to that shown in Fig. 7. When in the latter position rolls 333 are out of the way 25 and the sheets engaging the glue roll 254 travel freely beneath the same and are discharged to the assembling device J. When the rolls 333 are in the position shown in Fig. 8 the said rolls engage the roll 261 and assist in maintaining the 30 sheets out of contact with the roll 254 so that the sheets may pass through the device without being glued.

The shaft 331 is operated in the following manner: Attached to this shaft is a depending arm 35 334 best shown in Figs. 3 and 12. This arm is constructed with gear teeth 335 which mesh with gear teeth 336 on a lever 337. Lever 337 is pivoted at 338 to a bearing 339 secured to horizontal frame member 33. Lever 337 is further provided 40 with a pin 340 which is pivotally and slidably connected to arm 343 whereby the rolls 333 are moved as previously described.

The sheets on passing through the gluing device are delivered to the assembling device J, the 45 description of which will now follow. This assembling device is best shown in Figs. 11 and 12 and includes two temporary supports 351 and 352 which consist of plates disposed in proximity to the frame members 33 and 34 and somewhat 50 above the same. These plates are supported by hangers 353 and 354 which are pivotally connected to two posts 355 and 356 secured to the longitudinal frame members 33 and 34. The hangers 353 and 354 may swing toward and from 55 the center of the device to bring the temporary supports 351 and 352 in positions where the same may support the sheets fed from the gluing device H. When the sheet is in position upon these supports the said supports are moved away from 60 the center of the machine and the glued sheet is dropped, the same falling upon a table 357 secured to the longitudinal frame members 33 and 34.

The two temporary supports 351 and 352 are 65 moved in the following manner: Pivoted to the post 355 at 358 is a vertically extending lever 359. The upper end of this lever has pivoted to it a link 361 which in turn is pivoted to the hanger 354. The lower end of this lever has 70 pivoted to it a shorter link 362 which is pivoted at its other end to the hanger 353. The lower end of lever 359 also has pivoted to it a connecting rod 363 which in turn is pivoted to arm of a bell crank 364. Bell crank 364 is pivoted to a 75

bracket 365 secured to post 356 and the other end of said bell crank has pivoted to it a link 366 (Fig. 1) which in turn is pivoted to a pin 367 on an arm 368. Arm 368 is rotatably mounted on a stub shaft 369 which is secured to a bracket 371 mounted on horizontal frame member 34. The arm 368 has rotatably mounted on it a roller 372 which engages a cam 373 fast on shaft 161 previously referred to. As this shaft rotates, cam 373 oscillates the arm 368 which causes simultaneous movement of the two hangers 353 and 354 and the temporary supports 351 and 352 carried by the same toward and from each other. A counter weight 370 attached to the arm 368 maintains the roller 372 in engagement with the cam 373.

In order to prevent the sheets deposited upon the temporary supports 351 and 352 from following either of the supports, a number of vertically extending fingers 374 and 375 are employed which are disposed outwardly of the lateral edges of the sheets, and which are movable laterally in slots 380 in the temporary supports 351 and 352 and in the table 357. Fingers 374 are mounted on a cross head 376 which is attached to a vertically extending arm 377. Fingers 374 are similarly mounted on a cross head 378 which is attached to a vertically extending arm 379. Arm 377 is pivotally mounted in a bearing 381 secured to horizontal frame member 22 and arm 379 is similarly mounted in a bearing 382 secured to the horizontal frame member 23. The two arms 377 and 379 are connected together by means of two links 383 and 384 which are pivoted at their inner ends to a yoke 385 and at their outer ends to the arms 377 and 379. A rod 386 is slidably mounted in the yoke 385 and is guided for movement in a cross bar 401 secured to two depending brackets 402 and 403 attached to the longitudinal frame members 33 and 34. This rod has secured to it a clevis 387 which is pivoted to one arm 388 of a bell crank 389. Bell crank 389 is pivoted on a stub shaft 391 secured to a bearing 392 fast on horizontal frame member 23. The other arm 393 of this bell crank extends upwardly and has attached to it a cam 394. A roller 395 rotatably mounted on an arm 396 is adapted to engage this cam and to move the arm 393 inwardly. Arm 396 is attached to the shaft 71. The rod 386 has secured to it two collars 397 and 398 which are adapted to alternately engage the yoke 385 and to raise and lower the same, causing the fingers 375 and 374 to move toward and from each other. A tension coil spring 399 is connected to the collar 398 and to the link 383 and serves to move the cam 394 toward the shaft 71 and to lower the links 383 and 384 so as to move the fingers 374 and 375 toward one another. Fingers 374 and 375 by means of the movement imparted to the same through cam 394 center the sheets and arrange the same in proper position over the table 357.

For limiting the movement of the sheets delivered to the assembling device J an end stop 404 is employed which is secured to the upper end of a vertical arm 405 as shown in Fig. 11. This stop is disposed in proximity to the ironing mechanism L which consists of two rolls 406 and 407 and bears against the lowermost roll 406 thereof. The lowermost end of the arm 405 is pivoted to another arm 408 which in turn is secured to a shaft 409. Shaft 409 is mounted for rotation in a bearing 411 (Fig. 2) secured to the upright 39. This shaft has attached to its outer end a depending arm 412 which is drilled to re-

ceive the end of a connecting rod 413. Connecting rod 413 has two collars 414 and 415 attached to the same which engage the arm 412 on opposite sides and which serve to oscillate the shaft 409 as the connecting rod 413 is reciprocated. The connecting rod 413 is provided at its other end with a clevis 416 which is pivoted to an arm 417 mounted for oscillation on a stub shaft 418 secured to the bracket 75. Arm 417 has secured to it a bent arm 410 which has rotatably mounted at the end thereof a roller 419. Roller 419 engages a cam 421 which is mounted on shaft 85. A counter weight 422 secured to the arm 417 maintains the roller 419 in engagement with the cam 421. As the shaft 85 rotates, end stop 404 is moved from the position shown in Fig. 11 which arrests the movement of the sheet toward the ironing mechanism L to a position below the level of the table 357 permitting the sheet to be fed to the ironing mechanism.

In order to cause the sheets to descend from the temporary supports 351 and 352 to the table 357 and to further prevent the sheets from following either of said supports during their movement outwardly, a presser foot 423 is employed which is shown in Fig. 12 and is constructed in the form of a roller journaled in a clevis 424 secured to a depending rod 425. This rod is pivoted to a lever 426 which in turn is pivoted at 427 to a bracket 428 secured to the horizontal frame member 34. The lever 426 is provided at its end with a roller 429 which is adapted to engage a cam 431 fast on the shaft 71. This cam is so timed that as the temporary supports 351 and 352 are moved outwardly the presser foot 423 descends and forces the sheet down upon the table 357.

The sheets leaving the gluing device H are delivered to the assembling device J in the following manner: The two rolls 261 and 262 are positively driven by the chain 284 and the sheets resting upon the same are positively progressed toward the assembling device. Movement of the sheets is procured through these rolls whether the sheets are in engagement with the roll 254 or free therefrom and the movement of the sheet by these rolls is rapid enough so that the sheets are slid along the temporary supports 351 and 352 and until they engage the end stop 404.

The assembled stack of sheets after the required number of sheets have been assembled is moved from the assembling device J by means of the feed mechanism K to the ironing mechanism L. The feed mechanism K will now be described in detail which is best shown in Figs. 11 and 12. Operating in a slot 432 in table 357 is an auxiliary table 433 which is guided in said slot by means of guides 434. This table has secured to the underside thereof bearings 435 which journal a shaft 436. Shaft 436 has rigidly secured to it a bell crank 437 which has pivoted to the lower end of the same a link 438. Link 438 is pivoted to the upper end of a vertically extending arm 439 which is mounted on a shaft 441. Shaft 441 is journaled in bearings 442 secured to the horizontal frame members 22 and 23. The shaft 436 has also secured to it two arms 443 which are movable toward and from the auxiliary table 435. The movement of these arms is limited by means of double headed rivets 444 secured to said arms and operating through suitable holes in the table, not shown. As will be noted in the drawings, table 357 is slightly below the line of tangency of the two ironing rolls 406 and 407. The two rivets 444 when the arm 439 is moved

toward the left, as shown in Fig. 11, raise the assembled sheets so that the same are substantially in the horizontal plane of tangency of said rolls, whereby the assembled sheets are readily fed into the rolls.

The shaft 441 is operated in the following manner: Secured to the shaft 441 is an upwardly extending arm 445 which has pivoted to the upper end of the same a link 446. Link 446 is pivoted to a bell crank 447 which is mounted for oscillation upon the stub shaft 228. This bell crank is provided with a roller 448 (Fig. 17) which is adapted to engage a cam 449 secured to the gear 224. This cam is driven by shaft 85 through the gear 223 and serves to reciprocate the link 446 and to move the auxiliary table 433. A counter weight 440 secured to an arm 450 which is attached to shaft 441 operates to maintain the roller 448 in engagement with cam 449 and to move the auxiliary table 433 rearwardly to the position shown in Fig. 11. The table 433 is provided with a lip 451 which extends upwardly therefrom at the rearward edge of the same which engages the stack of sheets and progresses the same toward the ironing device L.

The ironing mechanism L as previously described, comprises two rolls 406 and 407 which are yieldingly held in engagement with one another. The roll 406 is provided with trunnions, not shown, which are journaled in bearings formed on the longitudinal frame members 33 and 34, not illustrated in the drawings. The roll 407 is similarly constructed and is provided with trunnions 458 and 459 (Fig. 1) which are journaled in bearings 452 which are attached to the longitudinal frame members 33 and 34. These bearings are of a type well known in the art and have bearing blocks therein in which the trunnions of the roll 407 are journaled and which are urged downwardly by means of suitable springs to provide yielding pressure between the rolls 407 and 406. The pressure between these rolls can be adjusted by means of adjusting screws 453 provided for the bearings 452. In this manner any desired pressure can be exerted upon the assembled sheets and as the stack of sheets pass between the rolls the same are ironed and pressed together and a composite structure is provided suitable for pressing into the flanged end wall structure.

The rolls 407 and 406 are driven in a manner best shown in Fig. 2. Attached to the shaft 276 is a sprocket wheel 454. A chain 455 passes over this sprocket wheel and another sprocket wheel 456 fast on the trunnion 459 of roll 407. The rolls 407 and 406 have intermeshing gears 461 and 462 by means of which the lowermost roll 406 is driven from the roll 407.

The ironed stack of sheets or the blank from which the end walls are constructed is fed from the ironing mechanism L to the trimmer N by means of conveyor M, best shown in Fig. 13. This conveyor consists of two rolls 463 and 464. The roll 463 is secured to a shaft 465 which is mounted for rotation in bearings 466 and 467 of which the bearing 467 is secured to the longitudinally extending frame member 33. A plate 468 connects the two bearings 467 and 466 together. Roll 464 is attached to a shaft 470 which is rotatably mounted in a bore of a sleeve 469 indicated in Fig. 11 in dotted lines, which is eccentrically disposed in said sleeve. Sleeve 469 is rotatably mounted in two bearings 471 and 472. Bearings 471 and 472 are secured to a plate 473 which is attached to a bracket 474 mounted on

the longitudinal frame member 33. By rotating the sleeve 469, the roll 464 can be moved toward and from the roll 463 to vary the pressure between the said rolls and to procure a feed for the blanks leaving the ironing device L or to permit said blanks to travel partly through the conveyor M without interference.

The rolls 463 and 464 are driven in the following manner: Attached to the end of the shaft 465 is a sprocket wheel 475. A chain 476 passes about this sprocket wheel and another sprocket wheel 477 secured to the trunnion 458 of the ironing roll 407. In this manner shaft 465 is positively driven. Attached to this shaft is a spur gear 478 which meshes with a corresponding spur gear 479 on shaft 470.

The sleeve 469 is rotated for the purpose of moving the roll 464 toward the roll 463 by a mechanism best shown in Fig. 11. Journaled in a bearing 481 secured to the longitudinal frame member 33 is a short shaft 482. This shaft carries a depending arm 483 which has pivoted to it a link 484. Link 484 is in turn pivoted to a bell crank 485 which in turn is pivoted at 486 to the upright 38. This bell crank has pivoted to it a link 487 which is in turn pivoted to an arm 488 secured to sleeve 469. When the arm 488 is moved toward the right, as viewed in Fig. 11, arm 488 is raised and the roll 464 is moved toward the roll 463.

The shaft 482 is oscillated in the following manner: Attached to this shaft upon the exterior of frame member 33 is a vertically extending arm 489. This arm has pivoted to it a link 491. Link 491 is in turn pivoted to a bell crank 492 which has rotatably mounted on it a roller 493. This bell crank is mounted for oscillation on the stub shaft 228. The roller 493 engages a cam 494 which is secured to cam 348 and travels with gear 224. A counterweight 495 secured to the bell crank 492 urges the roller 493 into engagement with cam 494.

To continue the feeding of the ironed stack of sheets to the trimmer N after conveyor M ceases to progress the same, a mechanism is employed which is best shown in Figs. 11, 13 and 14. Extending across the two longitudinal frame members 22 and 23 is a shaft 496. This shaft is journaled in bearings 497 and 498 attached to the frame members 22 and 23 and is held from axial movement therein by means of collars 499 and 500 secured to said shaft and engaging the ends of said bearings. At the center of this shaft is an arm 502 which is constructed with a hub 503 rigidly secured to said shaft. This arm extends upwardly and terminates in a yoke 504 which is provided with two spaced arms 506 and 507. These arms have attached to them slides 508 and 509 which are guided for sliding movement in guides 511 and 512. These slides have pivoted to them dogs 513 (Fig. 11) which operate at the point of tangency of the rolls and which take the ironed stack of sheets after the same leave the rolls and progress the said sheets up to the trimmer M.

The shaft 496 is operated in the following manner: Attached to the outer end of said shaft is a vertically extending arm 514 which is constructed with a hub 515 rigidly secured to said shaft. The upper end of this arm has pivoted to it a link 516 which extends rearwardly of the machine and which is best shown in Fig. 3. This link is pivoted to a bell crank 517 (Fig. 17) which carries a roller 518. This bell crank is mounted on the stub shaft 228. Roller 518 engages a cam 75

519 which travels with the gear 224. Roller 518 is maintained in contact with cam 519 by means of a counterweight 521 which is attached to an arm 522 secured to shaft 496. As the gear rotates the bell crank is oscillated and the shaft 496 correspondingly oscillated to operate the dogs 513 in a manner to feed the paper.

The trimmer N comprises a rotary table 523 and a rotary shoe 524 positioned above the same. 10 The trimmer also includes mechanism for urging the shoe 524 against the table 523 to cause the same to rotate. As the stack of sheets rotates the marginal portions of the same are trimmed by a cutter 525 best shown in detail in Fig. 14.

15 The table 523 is mounted on a flange 526 which is attached to a vertical shaft 527. This shaft is mounted for rotation in a vertical bearing 528 attached to a cross frame member 529 secured to the longitudinal frame members 33 and 34.

20 The shaft 527 is provided at its end with a collar 531 which engages a shoulder 532 formed in the bearing 528. A compression coil spring 533 is seated at one end against the shaft 527 and at its other end in a cap 534 secured to the end of the bearing 528. This spring maintains the table 523 at the elevation of the horizontal plane of tangency of the conveyor rolls 463 and 464.

25 The shoe 524 is similar to the table 523 and is mounted on a flange 535 which is attached to a vertically extending shaft 536. This shaft is slidably and rotatably mounted in a bearing 537 secured to a cross frame member 538 which is attached to the two longitudinal frame members 33 and 34. Rotatably mounted upon the upper end of the shaft 536 is a spur gear 539 which meshes with a spur pinion 541 fast on a shaft 542. The lower end of this shaft as shown in Fig. 13 is journaled in a bearing 543 which is attached to the longitudinal frame member 34. Shaft 542 carries a bevel gear 544 which meshes with another bevel gear 545 fast on a shaft 546 (Fig. 2). This shaft is journaled in a bearing 547 mounted on the longitudinal frame member 34 and carries a sprocket wheel 548. A chain 549 passes over this sprocket wheel and another sprocket wheel 551 fast on trunnion 459 of the ironing roll 407. This roll is driven as previously described and affords a drive for the gear 539. Gear 539 has attached to it a jaw clutch member 552 which can be shifted vertically by means of a forked arm 553, best shown in Fig. 14. This jaw clutch member is adapted to engage another jaw clutch member 554 pinned to the shaft 536. When the jaw clutch member 554 is brought into engagement with the clutch member 552, a drive is effected between gear 539 and the shaft 536 rotating shoe 524.

30 Lever 553 is pivoted at 555 to a standard 556 secured to the cross frame member 538. This lever has pivoted to its outer end a depending link 557 which in turn is pivoted to a bell crank 558 mounted for oscillation on a shaft 559 secured to a mounting 561 which in turn is attached to the longitudinal frame member 33. 35 The bell crank 558 has pivoted to it a link 562 which in turn is pivoted at 563 (Fig. 17) to an oscillating member 564. This member is in turn pivoted at 565 to a bracket 566 secured to the upright 27. The member 564 carries two rollers 567 and 568 which engage two cams 569 and 571 fast on the shaft 85. The two rollers 567 and 568 cause positive movement of the link 562 pivoted thereto, whereby the lever 553 is positively raised and lowered and the shoe 524 caused to

turn the stack of sheets delivered by the same through engagement with the table 523.

The cutter 525 as shown in Fig. 14 comprises two cutter disks 572 and 573 which are mounted on shafts 574 and 575. These shafts are journaled in bearings 576 and 577 attached to the longitudinal frame member 34. Upon the two shafts 574 and 575 are meshing spur gears 578 and 579, whereby the two cutter disks 572 and 573 are positively driven. A sprocket wheel 581 attached to shaft 574 is driven by means of a chain 582 which passes over a sprocket wheel 583 fast on shaft 459. This shaft is driven as previously described so that the cutter 525 operates continuously. The cutter 525 is situated a distance from the center of the shafts 536 and 537 equal to the radius of the blank to be cut from the assembled stack.

The assembled stack of sheets is fed into the trimmer N in such a manner that the said sheets just clear the cutter 525. Longitudinal movement of the assembled stack is terminated by means of a stop rod 584 which is slidably mounted in a guide 585 secured to an annulus 586, forming part of the press P which will be presently more fully described. This stop rod is pivoted to an arm 587 which is mounted for free swinging movement on shaft 496. As the arm 587 is oscillated stop rod 584 is caused to project above the level of the table 523 and to arrest movement of the assembled stack of sheets. The arm 587 is held in position on shaft 496, as shown in Fig. 14, between the hub 503 and a collar 588 secured to said shaft. Arm 587 has issuing forwardly from it an extension 589 by means of which said arm is oscillated in a manner to be presently described.

30 Operating in conjunction with stop rod 584 are shifter fingers 591 and 592 shown in Fig. 14. The fingers 591 are attached to a vertically extending arm 593 and the fingers 592 are similarly attached to a vertically extending arm 594. Both of these arms are provided with hubs 595 (Fig. 11) which are journaled on stub shafts 596 secured to brackets 597 attached to the longitudinal frame members 22 and 23. The hubs 595 have rigidly attached to them arms 598 and 599 which meet at the center of the machine and which are slidably and pivotally connected together by means of a joint 601 similar to the joint formed between the two arms 309 and 311 illustrated in Fig. 19. The arm 594 is oscillated back and forth by means of a link 602 which is pivoted at 603 to a bracket 604 secured to said arm. Link 601 is in turn pivoted to a crank arm 605 which is attached to a shaft 606. This shaft is journaled in a bearing 607 attached to longitudinal frame member 34 and carries another arm 608 extending outwardly therefrom. Arm 608 has pivoted to it at 609 a link 611 which in turn is pivoted at 612 to a swinging arm 613 mounted for oscillation on shaft 418 previously referred to. Arm 613 carries a roller 614 which engages a cam 615 fast on shaft 85. A spring 616 acts between the arm 608 and the longitudinal frame member 34 and maintains the roller 614 in contact with cam 615.

45 As shaft 85 oscillates the fingers 591 and 592 are brought together and engage the sheet in a manner to square the sheet up and center the same with respect to the table 523. Finger 592 is so arranged that the right hand edge of the sheet as viewed in Fig. 14 is brought right snug up to the cutter disk 572 so that as soon as the drive is effected the cutter 525 shears the assembled stack of sheets in a complete circle.

The stop 584 is operated by the arm 599 which rests upon the extension 589. As soon as the arm 599 is lowered, which occurs when the fingers 591 and 592 are brought together, stop rod 584 is raised. In this manner the assembled stack of sheets is held in proper position to permit the trimming device to commence to operate. As soon as the feed is procured between shoe 524 and the stack of sheets, fingers 591 and 592 are removed and the stop rod 584 is lowered. The trimming action continues until a blank has been cut from the stack of sheets in the form of a complete circle. This blank is then fed by the conveyor mechanism O to the press P.

As soon as the assembled stack of sheets is trimmed, shoe 524 is raised and the trimmed blank rests freely upon the table 523. A new stack of sheets is then ready to be inserted into the trimmer and is advanced into the same by the conveyor M. This stack of sheets engages the trimmed blank and feeds the same forwardly to a feed mechanism best shown in Fig. 11. This feed mechanism consists of two rolls 684 and 685. These rolls are attached to shafts 686 and 687, of which the shaft 687 is journaled in suitable bearings attached to the longitudinal frame member 33. The shaft 686 is journaled in a bearing 689 which is attached to an arm 691. Arm 691 is pivoted on a stub shaft 692 which is journaled in a bearing 693. Shaft 692 has attached to it an arm 694 which extends past the upright 27 and which has secured to the end of it a roller 695. This roller engages a cam 696 fast on shaft 85. As the cam 696 rotates the arm 691 the lower end of roll 684 is brought into contact with roll 685. Both of the rolls being driven, the cut blank is fed by means of the same to a position until the blank passes out of said rolls. The rolls 684 and 685 are driven in the following manner: Attached to the shaft 686 is a sprocket 697. A chain 698 passes over this sprocket and another sprocket 699 fast on shaft 465. This shaft is driven as previously explained whereby a drive is effected for the two rolls 684 and 685.

The conveyor mechanism O is best shown in Figs. 1 and 15 and consists of a finger 617 which is pivoted at 618 to a bracket 619 attached to a depending arm 621. This arm is attached to a shaft 622 which is journaled in bearings 623 secured to the uprights 27 and 28. The arm 621 has pivoted to it at 624 a link 625 which is rigidly secured to a plunger 626 which is slidably mounted in a guide 627. The guide 627 has a depending arm 628 which is pivoted at 629 to a bell crank 631. Bell crank 631 is mounted on a tubular shaft 632 which is rotatably mounted on a stub shaft 634 rigidly attached to a bracket 633 which in turn is bolted to the upright frame 28. Encircling the plunger 626 is a compression coil spring 635 which is seated at one end against the guide 627 and at its other end against a collar 636 fast on said plunger. By means of this spring the action of the conveyor mechanism O is so cushioned that injury to the fingers 617 is prevented in case the blank is not properly fed to the press. The bell crank 631 carries a roller 637 which engages a cam 638 fast on shaft 85. A spring 630 holds the roller 637 in engagement with said cam.

The press P consists of a die 639 and a plunger 641 cooperating therewith. These parts will now be described in detail. The die 639 is constructed with a circular hole 642 of the external diameter of the flange of the end wall to be formed from the circular blank fed to the press. This die is

mounted in the annulus 586 previously referred to, which is attached to the two uprights 27 and 28. Beneath the die 639 is a tube 643 which is constructed with a flange 644 arranged below the annulus 586. Bolts 645 pass jointly through the flange 644 and the die 639 and hold the parts rigidly secured to the said annulus. Encircling the tube 643 is a heater 646 which maintains the said tube at a suitable temperature and which serves to cause the glue in the blank to set after the flange has been formed, whereby the flange is maintained in proper form upon leaving the press.

The plunger 641 is of a diameter equal to the diameter of the hole 642 less twice the thickness of the flange to be formed on the end wall. This plunger is attached by means of bolts 647 to a head 648. Head 648 is rigidly secured to a vertically extending shaft 649 which is guided for vertical movement in a guide 651 attached to the transverse frame member 35. The plunger 641 is raised and lowered by means of a toggle lever system 652 which will now be described in detail. Formed on the underside of the transverse frame member 35 are bearings 653 to which are pivoted pairs of spaced links 654, by means of pins 655. Corresponding with the bearings 653 are other bearings 656 which are formed on the head 648. By means of pins 657 passing through these bearings two links 658 are pivoted to the head 648. The pairs of links comprising the links 654 and 658 are respectively pivoted to pins 659. Pivoted to these pins are links 661 which are constructed in the form of a yoke and which in turn are pivoted by means of other pins 662 to arms 663. These arms are attached to a shaft 664 which is journaled in bearings 665 secured to the uprights 27 and 28. Extending across the arms 663 is a shaft 666 which has pivoted to it two connecting rods 667. These connecting rods are secured to eccentric straps 668 which are rotatably mounted on eccentrics 669 secured to shaft 85. These eccentrics swing the arms 663 forwardly and rearwardly which through the links 661 operate the toggle mechanism 652 and cause the plunger 641 to raise and lower.

For centering the circular blank over the die 639 fixed stops 671 and 672 are employed of which the stop 671 is disposed at the other end of the die and the stop 672 at the sides. These stops are permanently secured to the die 639.

At the end of the hole 642 of die 639 a flexible finger 673 is employed which rides along the upper surface of the rearward portion of the die 639 and which is pivotally attached at 674 to a vertically extending lever 675. This lever is pivoted at 676 to the bracket 666. A link 677 is pivoted to lever 675 and is further pivoted to a bell crank 678. Bell crank 678 is pivoted at 679 to a bracket 681 which is attached to the transverse frame member 76, previously referred to. The bell crank 678 carries a roller 682 which engages a cam 683 fast on shaft 85. Cam 683 is so designed that the finger 673 is moved out of the way as soon as the plunger 641 commences to move downwardly. A counterweight 680 on bell crank 678 holds the roller 682 in contact with cam 683.

The discharge device Q consists of an inclined chute 701 which is provided with hubs 702 (Fig. 16). These hubs are received on a shaft 703 mounted upon the uprights 27 and 28. The chute 701 is positioned immediately below the tube 624 which is open at its lower end. As the formed

end walls are forced through the said tube the same are disposed upon the chute 701 which discharges the completed end wall away from the machine.

- 5 The operation of the invention is as follows: Paper is reeled off from the reel A and passes through the tensioning device B. The feed mechanism C carries the paper through the notching device E where the triangular corners 10 are cut out of the same and further carries the notched strip to the cut off device D. At the cut off device D sections of the sheet of paper are cut off at the vertexes of the notches formed therein and the said sections advanced to the 15 turning device F. By means of the notching device and the cut off device the sections become octagonal in shape. The turning device F operates to rotate every other sheet so that the alternate sheets have the grain running in 20 the opposite direction. By means of conveyor G the sheets are taken from the turning device and delivered to the gluing device H, whereby glue is applied by the glue roller 254 to the upper surface of the sheet. By means of the skip gluing mechanism I, every seventh sheet is held 25 away from the glue roller 254 so that the uppermost and lowermost sheets of the assembled stack are without glue on their uppermost and lowermost surfaces. The sheets are assembled one at 30 a time in the assembling device J, being singly disposed upon the auxiliary supports 433. As each sheet is positioned it is released from the auxiliary supports 433 and deposited upon table 357. When the desired number of sheets have 35 been assembled, the same are moved by the feed mechanism K to the ironing mechanism L. The rolls 406 and 407 of this device squeeze the sheets together so as to provide a substantially integral construction. The assembled stack of sheets 40 thus formed is moved by conveyor M to the trimmer N where the stack is cut circular in form by rotation of the stack to a diameter such as to form the finished product of the proper dimension. Conveyor mechanism O removes the 45 cut blank from the trimmer N and delivers it to the press P. Upon being received in the press the plunger 641 moves downwardly and bends the flange upon the blank forcing the formed structure along the tube 643. The heating element 50 646 causes the glue between the sheets of the flange to set so that when the formed structure is discharged from the said tube and upon the discharge device Q the end wall is ready to be assembled with the side wall structure and 55 formed into a complete container.

The advantages of my invention are manifest. The end walls are automatically constructed so that a minimum amount of labor is required. By means of my invention the end walls can be 60 accurately constructed so that variations in the dimensions thereof will be a minimum. By delivering the blanks directly to the press while the glue is still soft, the flanges are easily formed. By means of the heater used with the press the 65 flanges become set when the end wall is discharged from the machine. Due to the turning device employed warping of the end walls is eliminated and a structure of uniform strength procured.

70 Changes in the specific form of my invention, as herein disclosed, may be made within the scope of what is claimed without departing from the spirit of my invention.

Having described my invention, what I claim 75 as new and desire to protect by Letters Patent is:

1. In combination, a support for a strip of paper, means for cutting off sheets from the strip, means for assembling the sheets in overlying position, and means for turning certain of the sheets relative to the support about an axis 5 situated at right angles to the sheet and prior to assembly to cause the grain of certain of the sheets of the assembly to extend angularly with respect to the grain of other of the sheets.

2. In combination, a support for a strip of 10 paper, means for cutting off sheets from the strip, a rotatable table, means for conveying the cut sheets successively over said rotary table, means for urging the sheet overlying the table into engagement therewith, means for turning 15 the sheet while supported on the table, means for causing certain of the sheets to pass over said table without turning, and means for assembling the sheets in the positions of said sheet upon leaving the table. 20

3. In combination, a support for a strip of paper, means for cutting off sheets from the strip, a rotatable table, means for feeding the cut off strips successively to overlie said table, a presser foot disposed above said table, means 25 for bringing said presser foot down upon the sheet to urge the same into frictional engagement with the table, and means for rotating the sheet while engaged by the table and presser foot through predetermined angles of rotation. 30

4. In combination, a support for a strip of paper, means for cutting off sheets from the strip, a rotatable table, means for feeding the cut off strips successively to overlie said table, a presser foot disposed above said table, means 35 for bringing said presser foot down upon the sheet to urge the same into frictional engagement with the table, means for rotating the table through predetermined angles of rotation, and means for causing said feed means to feed 40 two sheets over the table for each operation of said table to procure alternate rotation of the sheets.

5. In combination, a gluing device, means for feeding sheets through the gluing device, an assembling device comprising a support, temporary supports disposed above said first named support and in a position to receive and support sheets above said first named support, means for feeding the sheets from said gluing device to overlie 45 said temporary supports, normally spaced fingers 50 adapted to engage the edges of the sheet resting upon said temporary supports and to move the sheets into a predetermined position thereon, and means for removing said temporary supports 55 while the sheets are held in position by said fingers.

6. In combination, a gluing device, means for feeding sheets through the gluing device, an assembling device comprising a support, temporary supports disposed above said first named support and in a position to receive and support sheets above said first named support, means for feeding the sheets from said gluing device to overlie 60 said temporary supports, normally spaced fingers 65 adapted to engage the edges of the sheet resting upon said temporary supports and to move the sheets into a predetermined position thereon, means for removing said temporary supports while the sheets are held in position by said fingers, and means for forcing the sheets downwardly along said fingers and toward said first named support. 70

7. In combination, a support for a strip of paper, means for cutting off sheets from said 75

- strip, a gluing device including a gluing roll, a presser roll for pressing sheets against said gluing roll, means for feeding the cut sheets over said presser roll and through the gluing device, 5 means for urging said presser roll toward said gluing roll, and means for periodically holding said presser roll away from said gluing roll to prevent gluing of certain of the sheets passing through the gluing device.
10. In combination, means for assembling glue coated sheets of paper, ironing rolls for pressing the glued sheets together and forming therefrom a composite blank, a rotating device for receiving and rotating the blanks formed by said ironing rolls, means for feeding the blanks from said ironing rolls to said rotating device, and a cutter adapted to cut the blank as the same is rotated.
15. In combination, a bearing having a vertical bore, a shaft slidably and rotatably mounted in said bearing, resilient means for urging said shaft upwardly, a rotatable table carried by said shaft, a second bearing disposed above said first bearing and having a bore concentric with the bore of said first bearing, a second shaft slidably and rotatably in said bore of the second bearing, a continuously rotating driven element mounted on said second shaft, a shoe carried by the end of said second shaft and superimposing said table, means for feeding a blank in between said shoe 20 and table, and means for lowering said shoe into engagement with the blank carried by said table, and means for effecting a drive between said driven element and said shaft.
25. In combination, a support for a strip of paper, means for cutting off sheets from the strip, means for assembling the sheets in overlying position, means for feeding certain of the cut sheets as formed from the strip to the assembling means, and turning means for turning certain of the sheets about an axis disposed at right angles to the sheet prior to assembly and feeding the sheets in turned position to the assembly means, to cause the grain of the turned sheets to extend angularly with respect to the grain of the sheets not turned.
30. In combination, a support for a strip of paper, means for cutting off sheets from the strip and forming the sheets substantially symmetrical about their centers, means for assembling the sheets in overlying position, means for feeding certain of the cut sheets as formed from the strip to the assembling means, and turning means for turning certain of the sheets through angles corresponding to the angles of symmetry prior to assembly and feeding the sheets in turned position to the assembly means to cause the grain of the turned sheets to extend angularly with respect to the grain of the sheets not turned.
35. In combination, a support for a strip of paper, means for cutting off sheets from the strip, means for assembling the sheets in overlying position, turning means for turning the sheets fed therethrough about an axis disposed at right angles to the sheet, means for feeding the cut sheets to the turning means and through the same to the assembling means, and means for rendering said turning means inoperable during the passage of certain of the sheets fed therethrough to cause the grain of said last named sheets to extend angularly with respect to the grain of the turned sheets.
40. In combination, two rotatable members disposed in axial alignment and having facing gripping surfaces, means for turning one of said members, means for bringing said members together to clamp a sheet of paper between the gripping surfaces thereof and cause rotation of the sheet and for moving the gripping surfaces apart to allow the passage of sheets through the space between the gripping surfaces without turning, 5 means for successively feeding sheets of paper to said rotatable members and through the same and means for holding said rotary members apart during the movement of certain of the sheets therethrough to prevent rotation thereof.
45. In combination, two rotatable members disposed in axial alignment and having facing gripping surfaces, means for turning one of said members, means for bringing said members together to clamp a sheet of paper between the gripping surfaces thereof and cause rotation of the sheet and for moving the gripping surfaces apart to allow the passage of sheets through the space between the gripping surfaces without turning, 10 means for successively feeding sheets of paper to said rotatable members and through the same, means for holding said rotary members apart during the movement of certain of the sheets therethrough to prevent rotation thereof and means for procuring alternate engagement and disengagement of the gripping surfaces of said rotatable members, as the sheets are fed thereto, to procure alternate rotation of the sheets.
50. In combination turning means for turning sheets fed thereto through specified angles of rotation, means for successively feeding sheets thereto, assembling means for assembling the sheets, means for feeding the sheets from the turning means to the assembling means, and means for rendering the turning means inoperative during the feeding of certain of the sheets to and from the same to cause the grain of certain of the assembled sheets to extend angularly with respect to the grain of other of the sheets.
55. In combination, a gluing device, means for feeding sheets through the gluing device, an assembling device comprising a support, temporary supports arranged above said first named support, and in a position to receive and support sheets above said first named support, means for feeding the sheets from said gluing device to overlie said temporary support, means for positioning the sheets while so supported, and means for moving the positioned sheets one at a time toward said first named support and depositing the same upon the previous sheets.
60. In combination, a gluing device, means for feeding sheets through the gluing device, an assembling device comprising a support, temporary supports arranged above said first named support, and in a position to receive and support sheets above said first named support, means for feeding the sheets from said gluing device to overlie said temporary support, means for positioning the sheets while so supported, means for moving the positioned sheets one at a time toward said first named support and depositing the same upon the previous sheets and means for pressing the assembled sheets together.
65. In combination, a gluing device, means for feeding sheets through the gluing device, an assembling device comprising a support, means for moving the sheets from the gluing device and to an elevated position over said support, means for arresting the sheets while over the support, means for adjusting the position of the sheets while overlying the support, and means for moving the sheets bodily in the direction of their thickness one at a time from their adjusted position toward

the support and depositing the same upon the previous sheets.

19. In combination, a gluing device, means for feeding sheets through the gluing device, an assembling device comprising a support, means for moving the sheets from the gluing device and to an elevated position over said support, means for arresting the sheets while over the support, means for adjusting the position of the sheets while 10 overlying the support, means for moving the sheets bodily in the direction of their thickness one at a time from their adjusted position toward the support and depositing the same upon the previous sheets, and means for pressing the assembled sheets together.

20. In combination, a gluing device, means for feeding sheets through the gluing device, an assembling device comprising a support, means for feeding the glued sheets in the direction of their 20 length one at a time from said gluing device to said assembling device and into a position above said support and means for feeding the sheets one at a time in a transverse direction toward said support to deposit the sheets one upon the other.

21. In combination, a gluing device, means for feeding sheets through the gluing device, an assembling device comprising a support, means for feeding the glued sheets in the direction of their 30 length one at a time from said gluing device to said assembling device and into a position above said support, means for feeding the sheets one at a time in a transverse direction toward said support to deposit the sheets one upon the other, and means for pressing the sheets together.

22. In combination a gluing device, adapted to coat sheets on one surface thereof, an assembling device, feed means for feeding a number of glued sheets from said gluing device to said assembling 40 device, and means for rendering said gluing device inoperative during the feeding of one of the sheets through the gluing device to cause said feed means to deliver an unglued sheet to the assembly device to be disposed in juxtaposition 45 with respect to the outermost glued surface to form a stack of sheets free from glue upon the outermost surfaces thereof.

23. In combination a gluing device adapted to coat sheets on the upper surface thereof, an assembling device including a support, feed means

for feeding sheets one at a time from the gluing device to a position above the support, means for depositing the sheets one upon the other on said support, and means for rendering said gluing device inoperative during the feeding of one of the sheets through the gluing device to cause said feed means and depositing means to deliver to and deposit upon the stack an unglued sheet.

24. In combination, a rotatable table, a driven shoe superimposing said table, intermittently operated feed means for feeding blanks in between said table and shoe, said means ceasing to feed blanks for a period after the delivery of each blank, means for bringing said shoe into engagement with said table to procure rotation of the 15 blank, means for causing operation of said last named means, during cessation of movement of said feed means, and a cutter for cutting the blank during rotation of said blank.

25. In combination, a rotatable table, a rotatable shoe superimposing said table and coaxially disposed relative thereto, means for guiding said shoe for axial movement relative to said table, a transmission for driving said shoe including a constantly driven member, clutch means between 20 said shoe and member, means for moving said shoe toward said table, and means operable through movement of said last named means for operating said clutch to effect a drive for said shoe.

26. In combination, a rotatable table, a rotatable shoe superimposing said table and coaxially disposed relative thereto, means for guiding said shoe for axial movement relative to said table, normally disconnected drive means for driving 30 said shoe and means for simultaneously moving said shoe toward said table and connecting said shoe with said drive means.

27. In combination, a rotatable table member, a rotatable shoe member superimposing said table 40 member and coaxially disposed relative thereto, means for guiding one of said rotatable members for axial movement relative to the other rotatable member, normally disconnected drive means for driving one of said rotatable members, and means 45 for simultaneously moving the axially movable rotatable member toward the other rotatable member and connecting the drive means with the rotatable member driven thereby.

SWAN SMITH.

50
